UNITED STATES PATENT OFFICE.

GEORGE H. TANSLEY, OF HARTFORD, CONNECTICUT, ASSIGNOR TO COLT'S PATENT FIRE ARMS MANUFACTURING COMPANY, OF HARTFORD, CONNECTICUT, A CORPORATION OF CONNECTICUT.

AUTOMATIC PISTOL.

Application filed February 29, 1924. Serial No. 695,916.

To all whom it may concern:

Be it known that I, GEORGE H. TANSLEY, a citizen of the United States, residing in Hartford, in the county of Hartford and 5 State of Connecticut, have invented certain new and useful Improvements in Automatic Pistols, of which the following is a specification, reference being had to the accompanying drawings, forming a part here- 10 of.

The invention relates generally to automatic firearms, and more particularly to automatic pistols in which the several operations, such as the opening of the breech 15 after firing a shot, the extraction and ejection of the empty cartridge shell, the cocking of the hammer, the presentation and introduction of a loaded cartridge to the chamber of the barrel, and the closing of the 20 breech are automatically effected through the energy of recoil of the breech closing part.

The large caliber automatic pistol of this description, which is the most effective and 25 therefore most to be desired for military purposes under service conditions in the field where great striking power is required in a pistol, is not so desirable as the small caliber automatic pistol for practice pur- 30 poses, mainly because of the greater cost of the powerful ammunition.

Small caliber automatic pistols specially adapted for practice purposes, as heretofore constructed, have usually been much lighter 35 in weight and differed to a marked degree from the large caliber service pistol in appearance, operation and handling, so that practice with them has not adequately met the requirements in the military branches of 40 the service of familiarizing the user there- of with the handling of the service pistol. Moreover, the cost of supplying two complete automatic pistols, one adapted for service in the field, and the other adapted 45 for target practice, has also been found unduly burdensome.

It is an object of the invention to pro- 50 vide a small caliber automatic pistol adapted for practice purposes which, in appear- ance, weight and handling, approximates a large caliber automatic pistol adapted for military service and which overcomes the

necessity of providing a complete automatic pistol specially adapted for practice in addition to the regular service pistol. This object is attained by utilizing a common frame, which frame may be the frame of a standard service pistol, and by interchangeably associating with said frame, at will, one of two sets of parts, each set 55 comprising a barrel, a breech slide, and a magazine, said sets of parts being adapted to accommodate, respectively, the powerful large caliber service cartridges or the 60 small caliber practice cartridges. 65

It is a further object of the invention to provide an automatic pistol of the general class hereinbefore described with a simple yet highly efficient buffer for absorbing 70 some of the energy of recoil of the breech closing part.

It is a further object of the invention to provide an automatic pistol of this general class with novel and improved means for stopping the breech closing part in a 75 rearward position after the magazine has become empty and the last cartridge has been fired.

With these and other objects in view, the invention consists in the features of construction and the combination of elements which will be hereinafter more fully set forth, and the novel features thereof pointed out in the claims at the end of the specification. 80 85

In the accompanying drawings:

Figs. 1 and 2 show the novel improved small caliber automatic pistol adapted for practice purposes, respectively, in a front view and in a left-hand side view; in the 90 front view, the greater portion of the handle has been broken away.

Figs. 1^a and 2^a show, for comparison with the pistol shown in Figs. 1 and 2, corresponding views of a large caliber automatic 95 service pistol, being that adopted by the United States Government as the standard pistol for the various branches of the military service.

Fig. 3 is a central vertical longitudinal 100 section, on an enlarged scale, of the upper portion of the practice pistol; the greater portion of the barrel is shown in elevation and the breech slide is in the rearward

open position which it occupies after the last cartridge has been removed from the magazine and fired.

Fig. 3^a is a central vertical longitudinal section, on the same scale as Fig. 3, and for comparison with said figure, of the upper portion of the service pistol; the breech slide is shown in its rearward open position, cartridges are shown remaining in the magazine, and the barrel and the portion of the magazine shown appear in elevation.

Fig. 4 is a central vertical longitudinal section through the upper portion of the improved practice pistol with the greater portion of the barrel and the portion of the magazine shown appearing in elevation; the breech slide is shown in its forward barrel closing position and the hammer, in its cocked position.

20 Figs. 5, 6 and 7 show the breech slide of the improved practice pistol, detached, respectively in a front view, in a vertical transverse section taken some distance in rear of the front face of the breech closing 25 part of the slide and as seen from the front, and in a central vertical longitudinal section.

25 Figs. 5^a, 6^a and 7^a show the breech slide of the service pistol, detached, in views corresponding to and for comparison with 30 Figs. 5, 6 and 7, respectively.

Fig. 8 shows the reaction spring of the improved practice pistol in the uncom-pressed condition and in its relation to the front tubular plug and the guide rod and 35 buffer; the buffer is shown in central vertical longitudinal section.

Fig. 9 is a rear end view of the reaction spring guide rod and the buffer.

40 Figs. 10 and 11 show the barrel of the im-proved pistol, detached, and with the ejector seated thereon, respectively, in a left-hand side view and in a rear end view.

Similar reference numerals refer to similar parts throughout the several views.

45 In the drawings, the frame 1, which, in accordance with the invention, is common to the large caliber service pistol and to the small caliber practice pistol, is shown pro-vided with the usual hammer 7, the sear 8, 50 the safety or disconnector 9, the grip-lever 10, the combined sear and safety spring 11, the combined slide-lock and hammer-lock 12 and the magazine catch 21 all of which correspond in structure and function with 55 the similar parts shown and described in the prior patents for firearms granted to J. M. Browning, No. 984,519 dated February 14, 1911, and No. 1,070,582, dated August 19, 1913, and further description of these ele-60 ments, except as they co-operate with other elements of the novel improved pistol, is therefore believed to be unnecessary.

In the large caliber service pistol, see 65 Figs 2^a and 3^a, the barrel 2^a is connected to the frame 1 by means of a link 14^a and the

hinge pin 13 passing through aligned trans-verse holes in said frame and said link, which connection permits the barrel to have limited longitudinal movement for locking it to and unlocking it from the breech slide 70 3^a in the manner fully set forth in the afore-mentioned prior Patent No. 984,519.

In the improved practice pistol, the barrel 2 has near its rear end an integral downward projection or lug 14 having a laterally reduced lower portion 14', see Fig. 11; said lug fits loosely in a corresponding seat in the frame 1 some distance forward of the magazine seat in said frame, see Figs. 3 and 4, and is provided with a transverse hole to receive the same pin 13, used alterna-tively to connect the movable barrel 2^a of the large caliber service pistol to the frame, to fixedly secure the small caliber barrel 2 to the frame, compare Figs. 3 and 3^a. 85

A comparison of these two figures, and also of Figs. 1 and 1^a, shows that the barrel 2 is considerably heavier than the barrel 2^a, because the two barrels are of substantially the same external diameter, but have bores of different calibers. This additional weight in the barrel 2, being located well for-ward with reference to the pistol as a whole, reduces the tendency in arms of this class to disturb the aim after each shot because of the upward kick at the muzzle. Furthermore, it compensates for the de-creased weight of the breech slide 3, now to be described, as compared with the weight of the breech slide 3^a of the service pistol, so that the total weight of the practice pistol is kept substantially equal to the total weight of the service pistol, which is desirable in order to more readily familiarize the shooter with the handling of service pistols while using the practice pistol. 100

The breech slide 3 of the improved prac-tice pistol like the breech slide 3^a of the large caliber service pistol, is mounted on the frame 1, together with its cooperating barrel, upon the usual guides which keep said slide vertically on the frame. The rear portion of the slide 3 forms, in a usual manner, the breech closing block 3' which carries the longitudinally extending spring-retracted firing pin 6 adapted to be struck by the hammer 7. Forward of said breech closing block 3' the slide covers the barrel, having substantially the shape of an inverted U in transverse section except at its for-ward end, where the bottom of the slide is closed in the usual manner by the down-wardly extending tubular abutment 3'', see Figs. 5 and 7, which receives the forward end of the reaction spring 4, see Figs. 3 and 4. 110

From the foregoing description, and from a comparison of Figs. 1 and 2 with Figs. 1^a and 2^a, it will be evident that the breech slide 3 of the improved practice pistol closely 120 125 130

resembles in external appearance and configuration the breech slide 3^a of the service pistol, but, as is more particularly brought out by the comparison of Figs. 3, 5, 6 and 7 with Figs. 3^a, 5^a, 6^a and 7^a, differs therefrom to a marked degree in weight, being of a much lighter construction than the slide 3^a. In these views, the walls of the forward portion of the slide covering the barrel are shown to be much thinner in the breech slide 3 than in the breech slide 3^a, and the rear breech closing portion 3' of the slide 3 is shown to be greatly lightened by the skeleton construction shown in the transverse section 15 Fig. 6 and in dotted lines in Fig. 7.

This lighter construction of the breech slide 3 as compared with the slide 3^a, is as should be, for the reasons hereinbefore stated and also for the following reasons: 20 While a breech slide of great weight is highly necessary in the service pistol in which the energy of recoil of the slide must not only compress the reaction spring in its rearward movement, but must also move the 25 barrel rearward until its rear end is swung down to effect the unlocking of the breech slide and barrel, in the automatic practice pistol adapted to use cartridges having light charges of powder as compared with the 30 heavy charges required in the service ammunition, such a construction would not be practicable, because the pressure of the gases developed by the light charges would not 35 be capable of opening the breech to the required extent against the tension of the reaction spring.

The forward end of the breech slide of the improved practice pistol is provided with the usual bushing 16 for supporting the forward end of the barrel 2, and this bushing has a downward projection adapted to form an abutment for receiving the thrust of the reaction spring 4, which returns the breech slide to its forward barrel-closing position. 40 The reaction spring 4 is less powerful than the reaction spring 4^a of the service pistol, for the same reason as that which makes it necessary to have the slide 3 lighter than the slide 3^a of the service pistol. Said reaction spring extends at its forward portion into the usual tubular plug 24 adapted to lock the bushing 16 against rotation in the usual manner and to transmit the tension of said reaction spring to the bushing 16 and, 45 through it, to the breech slide 3. At its rear end, the tension of the reaction spring is transmitted to the frame through the reaction spring guide rod 5, the enlarged head 5' of which, see Figs. 3 and 4, rests against a vertical shoulder 1' on the frame, in a manner similar to the known construction in the large caliber service pistol, see Fig. 3^a, and as disclosed in the prior Patent No. 984,519, hereinbefore referred to.

50 To cushion the blow of the breech slide 3

at the end of its recoil, a compact and highly efficient buffer 15 is provided. Said buffer 15 may comprise suitable resilient means, such as a plurality of resilient disks, supported forward of the head 5' of the reaction 70 spring guide rod 5, said disks being preferably frictionally held on said rod, see Figs. 3, 4 and 8.

The rear end of the reaction spring 4 rests against the foremost disk, and when the 75 breech slide nears the limit of its rearward movement, the rear surface of the tubular abutment 3'' at the forward end of the breech slide strikes the foremost of said resilient disks, and thus the blow of the 80 slide is transmitted to the frame through the resilient buffer and thereby effectively cushioned. Moreover, the buffer also serves to limit the recoil of the slide, and by its rebound after it has arrested the slide, the 85 buffer assists the reaction spring 4 in returning the breech slide to its forward breech closing position.

Since the frame of the improved practice pistol is the same as that used in the service pistol, and therefore has a magazine seat in the handle capable of receiving a magazine 18^a adapted to hold the large caliber service cartridges, see Fig. 3^a, a separate magazine adapted to occupy said seat and to hold and present small caliber practice cartridges in position to be transferred by the breech slide into the barrel chamber, is provided for the practice pistol. In Figs. 3 and 4, the upper portion of one form of magazine which will serve this purpose is shown. Such magazine may comprise an inner casing 18 adapted to receive said small caliber cartridges and having a magazine follower 19 actuated by a spring 20 to raise the cartridges to the mouth of the magazine; said inner casing 18 is enclosed except at its upper end in an outer casing 18' adapted to fit the seat in the handle of the frame 1. Suitable means secure the inner casing 90 against movement relative to the outer casing; such means may comprise those shown in Figs. 3 and 4, where the upper portion of the inner casing 18 is secured against lateral movement by the upper portions of the sides of the outer casing 18 which are bent inward against the sides of the inner casing, see Fig. 4, and against movement in a direction longitudinally of the pistol by a filler piece 18'', see Fig. 3, extending from the rear wall 95 of the outer casing 18' to the rear wall of the inner casing 18 and keeping the forward wall of said inner casing resting against the forward wall of the outer casing. The outer casing 18' is provided with a recess, not shown, for co-operation with the magazine catch 21 in the usual manner to keep the magazine in its seat.

Another feature of the invention consists 100 in the provision of novel improved means 105

for stopping the breech slide 3 in a rearward position, as shown in Fig. 3, after the last cartridge has been removed from the magazine and fired, thereby notifying the shooter that the magazine is empty. Such means comprise the magazine follower 19, which has for this purpose an integral stop 19' provided with a substantially vertical rear shoulder adapted, when the follower is moved to its uppermost position under the tension of the follower spring after the recoil of the breech slide due to the firing of the last cartridge, to project into the path of the central longitudinal depending rib 15 on the breech closing block 3', so that in the first part of its return movement under the tension of the reaction spring, said slide is arrested by the engagement of the vertical rear shoulder on the stop 19' of the follower 20 19 with a corresponding shoulder formed by the front end of the said depending rib on the breech closing block 3'. In order that such stoppage may be effected without shock, it is desirable that said stop be constructed so as to cushion the blow of the breech slide when it engages the stop. By the novel improved construction this object is attained by forming the stop 19' as a relatively thin integral rear portion or tongue 25 connected to the follower body proper only at its lower end, see Fig. 3. The follower 19, particularly the rear portion thereof comprising the integral stop 19' being made of metal having a spring temper, the integral stop 19' thereon will act in the manner of a stiff leaf spring, so that, when its upper vertical rear surface is struck by the slide, said stop can yield forwardly, thereby cushioning the blow of the slide, and thus 30 avoiding all possibility of battering of the contacting surfaces on the stop and the slide by the repeated stopping of said slide in the use of the improved pistol. In this way an effective yielding stop for the breech slide 35 is provided without the use of any extra parts. If the magazine is removed when the parts are in the position shown in Fig. 3, the breech slide 3 will be released and then returned to its forward barrel closing position by the tension of the reaction spring 4. Should it be desired to retain the slide in the open position, while the magazine is being removed and a filled magazine inserted into the seat in the frame, this may be done 50 by moving the slide rearward a short distance from the position shown in Fig. 3 until the recess 3''' in the slide, see Fig. 2, stands above the usual upward projection on the crank arm 13' of the barrel securing pin 13, and then moving said arm by pressure against the thumb-piece thereon upwardly, thereby bringing the square rear end of said projection in front of the square rear end of said recess 3''' in the slide. The 55 slide is thus kept at the rear in the open

position until the crank arm 13' is manually depressed to withdraw the projection thereon from said recess in the slide.

The construction and arrangement of the spring retracted firing pin 6 of the practice pistol corresponds with that of the firing pin 6^a of the service pistol, compare Figs. 3 and 7 with Figs. 3^a and 7^a, except that the firing point of the firing pin 6 is square in order to more effectively co-operate with the small caliber rim fire ammunition, whereas the point of the firing pin 6^a is rounded.

The extractor 22 of the practice pistol is arranged in a longitudinal seat therefor on the right-hand side of the breech slide 3 in a manner similar to the arrangement of the extractor 22^a in the slide 3^a, and as disclosed in the prior Patent No. 984,519 hereinbefore referred to. It is obvious, however, that the hooked forward portion of the extractor 20 which projects beyond the front face of the breech closing block 3' is necessarily arranged nearer to the center of the breech block than is the corresponding portion of the extractor 22^a, compare Figs. 5 and 5^a. 25 Also, the said hooked portion of the extractor 22 is preferably pressed inward with less tension than the corresponding portion of the extractor 22^a.

The breech closing block 3' is provided with a recess in its front face, see Fig. 4, to receive the head of a cartridge seated in the barrel chamber, and the barrel 2 has on its right-hand side a horizontal recess, see Fig. 11, having a laterally and outwardly inclined forward wall to receive the forward end of the extractor in the usual manner when the breech slide is in its forward position. The barrel is further provided with a short rearward projection below the bore 105 thereof, said projection having an upward and forward inclined rounded guiding surface, see Figs. 3, 4 and 11, to guide the bullet end of each cartridge 100 successively into the barrel chamber during its transfer from the magazine into 110 said chamber by the forward movement of the breech slide.

In the construction of the improved practice pistol it has been found desirable to mount the ejector 23 on a part of said pistol, such as the barrel 2, which is interchangeable with a corresponding part of the service pistol. To this end, the barrel 2 has at its rear end and on the left-hand side thereof a longitudinal groove ending in a transverse groove, said groove forming a seat for the corresponding forward portion of the ejector 23, see Figs. 10 and 11, whereby the same is held against longitudinal and rotary movement relative to said barrel. The wall of the breech slide 3 covering the barrel serves to keep the ejector in its seat on the barrel 2 when the parts are in assembled position. The inward projection 23' 115 120 125 130

at the rear end of the ejector 23' is adapted to engage the head of a cartridge being extracted by the recoil of the breech slide and throw said cartridge laterally through the 5 ejection opening in said breech slide in the usual manner.

From the foregoing description of the construction and operation of the various parts of the novel improved pistol it is believed that the operation of the pistol as a 10 whole will be readily understood and that further description of such operation is unnecessary.

It will be seen that a construction has been provided whereby an automatic pistol of the "locked" type, that is, one in which the breech slide is positively locked in barrel closing position until the bullet has left the barrel after firing a shot, can be readily converted, at will, by the interchange of relatively few parts, from a large caliber pistol adapted for military service in the field to a small caliber practice pistol of the "blow back" type, that is, one in which the 20 breech slide is held in barrel closing position only by its inertia and the tension of its reaction spring, or vice versa.

In order for the shooter to be thus equipped with practically two automatic 30 pistols adapted for diverse uses, he need carry only, in addition to the standard large caliber service pistol, as shown in Figs. 1^a and 2^a, the small caliber barrel 2 and breech slide 3 with the parts mounted thereon, the reaction spring 4 and parts immediately associated therewith as shown in Fig. 8, and the magazine 18, 18' adapted to carry the small caliber cartridges. The 40 change from an automatic service pistol to the improved target pistol may then be readily effected in the following manner:

The magazine catch 21 is pressed toward the right to release the magazine 18^a which then drops out of its seat in the handle. 45 The breech slide 3^a is then drawn rearward until the pivot pin 13 can be laterally removed to the left. The barrel 2^a, breech slide 3^a and reaction spring 4^a with the reaction spring guide rod 5^a can now be slid 50 forwardly off the frame 1. The barrel 2 of the practice pistol, the breech slide 3 and the reaction spring 4 with its guide rod 5 carrying the buffer 15, all of which have been first brought together in their assembled relation 55 with each other substantially as shown in Fig. 4, except that before these parts are assembled on the frame 1, the head of the reaction spring guide rod 5 rests against the forward face of the barrel lug 14, are 60 then together slid upon the frame 1 from the front until the transverse hole in the barrel lug is in line with the transverse holes in the frame, when the pin 13 is inserted into said aligned holes from the 65 left and thereby locks all said parts in as-

sembled relation with the frame 1. A magazine 18, 18', adapted to hold small caliber cartridges is now inserted in the magazine seat in the handle of the frame 1, in which it is kept by the magazine catch 21. 70 The arm is now ready for use as a practice pistol. The change from the practice pistol to the service pistol is effected in substantially the same manner.

While I have hereinbefore described my 75 invention as embodied in a small caliber practice pistol, it will be obvious that certain features thereof are applicable to other firearms, and I therefore do not intend to limit their application to this particular 80 type of firearms. Various changes in form and arrangement of parts also may be made without departing from the spirit of the invention.

What I claim and desire to secure by 85 Letters Patent is:

1. In a small caliber automatic pistol, the combination of the frame of a standard large caliber automatic pistol of the "locked" type, a small caliber barrel 90 mounted on said frame, and a "blow back" breech slide of similar configuration to, but of considerably less weight than, the breech slide of said standard pistol.

2. In a small caliber automatic pistol, the combination of the frame of a standard large caliber automatic pistol of the "locked" type, with a fixed small caliber barrel and a "blow back" breech slide, said barrel and breech slide having substantially 95 the outside configuration and the combined weight of the corresponding parts in said standard pistol, whereby a small caliber automatic pistol similar in appearance and operation to said standard pistol is produced. 100

3. In a small caliber automatic pistol, the combination of the frame and the parts more or less permanently associated with 110 said frame of a standard large caliber automatic pistol having a recoiling barrel and a locked breech slide, a small caliber barrel mounted on said frame, and a "blow back" breech slide associated with said frame and with said barrel, said breech slide being 115 similar in general configuration but considerably lighter in weight than the breech slide of said standard pistol.

4. In a small caliber automatic pistol, the combination of the frame of a standard large caliber automatic pistol, a barrel fixedly mounted on said frame, a breech slide of similar configuration to but of considerably less weight than the breech slide of said standard pistol, associated with said frame and with said barrel, a reaction spring to return said breech slide after the recoil thereof due to the firing of a shot, a guide rod resting against said frame and supporting the rear portion of the reaction spring, 120 125 130

- and a buffer carried by said guide rod, said buffer serving to absorb the excess of energy of the breech slide at the end of its recoil and co-operating with the reaction spring to 5 return the breech slide.
5. In a small caliber automatic pistol, the combination of the frame of a standard large caliber automatic pistol having a recoiling barrel and a recoiling breech slide 10 normally locked to said barrel, a small caliber barrel fixedly mounted on said frame, a breech slide of generally similar configuration to, but of considerably less weight than, the breech slide of said standard pistol, and resilient means for cushioning the blow of the breech slide at the end of its recoil.
6. In an automatic pistol, the combination of a frame, a recoiling breech slide supported thereby, a reaction spring for returning said slide after the recoil thereof, a guide rod for the rear portion of said spring having a head resting against said frame, and a buffer for said slide surrounding said rod between the end of said spring and said head.
7. In an automatic pistol, the combination of a frame, a recoiling breech slide supported thereby, a reaction spring, a guide rod for the rear portion of said spring having a head, and a buffer for the breech slide arranged between said head and said spring, said buffer comprising a plurality of resilient washers.
8. In an automatic pistol, the combination of a frame, a recoiling breech slide supported thereby, a reaction spring, a guide rod for said spring resting against said frame, a shoulder on said guide rod, and a buffer for the breech slide forward of said shoulder and frictionally held on said guide rod.
9. In an automatic firearm, the combination of a frame, a cartridge magazine seated in said frame and having a follower for automatically moving the cartridges toward the mouth of the magazine, a barrel, a breech closing member having longitudinal movement to open and close the breech of the barrel, and means for stopping said member in a rearward position without shock after the last cartridge has been removed from the magazine and fired, said means comprising an integral resilient portion of said follower adapted to project into the path of a shoulder on said breech closing member.
10. In an automatic firearm, the combination of a frame, a barrel, a breech closing member movable to open and close the breech of the barrel, a cartridge magazine carried by said frame, a follower for automatically moving the cartridges toward the mouth of
- said magazine, and means for stopping said breech closing member in a rearward position without shock after the last cartridge has been removed from the magazine and fired, said means comprising an integral spring tongue on said follower adapted to project into the path of a shoulder on said breech closing member.
11. In an automatic practice pistol, the combination of the frame of a standard automatic service pistol, a barrel adapted to use small caliber cartridges mounted on said frame, and a "blow back" breech slide covering said barrel and similar in external configuration to the breech slide of said service pistol but considerably lighter in weight to permit the proper automatic functioning of the pistol with the small caliber ammunition, whereby an automatic practice pistol similar in appearance and operation to the standard service pistol is produced.
12. As an article of manufacture, a convertible automatic pistol comprising a single frame, a plurality of breech slides of different weights but of similar configuration adapted to be selectively mounted on said frame, a plurality of barrels of different calibers corresponding to the breech slides of different weights, and a plurality of magazines adapted to receive cartridges corresponding to the different barrels, whereby automatic pistols of different power and adapted for diverse uses but similar in general appearance and operation may, at will, be produced by combining any one of the sets of parts comprising a barrel, a breech slide and a magazine with said single frame.
13. As an article of manufacture, a convertible automatic pistol comprising a common frame and interchangeable sets of parts adapted to be selectively operatively associated with said common frame, said sets of parts comprising respectively, a large caliber barrel, a breech slide corresponding thereto and a magazine adapted to receive large caliber cartridges corresponding to said barrel and breech slide, and a small caliber barrel, a breech slide of similar configuration to said first named breech slide but of considerably less weight, and a magazine adapted to receive small caliber cartridges corresponding to said small caliber barrel and the breech slide associated therewith, whereby automatic pistols of similar appearance and operation but adapted for diverse uses may, at will, be produced by operatively associating either of said sets of parts with said common frame.
- This specification signed at Hartford, in the county of Hartford and State of Connecticut, this 26th day of February, 1924.
- GEORGE H. TANSLEY.
